METHOD OF FORMING ABRASIVE SURFACES
UPON HIGH-SPEED GRINDING WHEELS

Folliard F. Gilmore, Wellesley Hills, and Frank W. Kotler, Watertown, Mass.; said Kotler assignor to said Gilmore

Application August 2, 1940, Serial No. 349,622

4 Claims. (Cl. 82—1)

This invention relates to a method of making high-speed grinding wheels and to the grinding wheels prepared in accordance with such method.

This application is a continuation in part of our co-pending application, Ser. No. 250,525, filed January 12, 1939, for "Abrasive surfaces."

In grinding and polishing operations, for efficient and high-speed production purposes, it is often desirable that the abrasive-containing surface should be moved at a high speed in relation to the work, speeds of between 5,500 and 6,000 superficial feet per minute being considered best practice. The abrasive is ordinarily held within a hardened matrix which is applied upon an annular surface of a rotatable wheel, tube, shaft or spindle. The speed of rotation is such that centrifugal force tends to tear the abrasive-containing matrix away from the metallic surface on which it rests and in high-speed wheels of this kind the problem of securing the abrasive-containing matrix to the metallic supporting surface is one which has been the subject of much study and attention.

The difficulty of securing the matrix to the metal surface of the wheel is especially pronounced in the case of the matrices which contain diamond particles. The problem involved in supporting diamond particles in proper position for use in a high-speed grinding wheel is set forth in our application, Ser. No. 212,306, filed by us June 7, 1938, wherein is disclosed a suitable matrix and a method of making same, whereby diamond particles may be supported, and a supporting matrix may be built up.

The present invention is directed more particularly to the method, and the means, whereby the matrix may be securely bonded to the underlying metallic surface on which it rests. While we shall refer herein to a matrix which contains diamond particles, we believe that the method and means herein described are useful for bonding any abrasive-containing matrix to its supporting metal surface.

Referring to the annexed drawing forming a part of this specification:

Fig. 1 shows in cross section a so-called cup-shaped grinding wheel of conventional design, and illustrates the type of structure to whose manufacture our invention is adapted.

Fig. 2 shows, in section and perspective, the shape of a portion of the annular periphery of this wheel, at the start of operations.

Fig. 3 shows in section the manner in which the metal surface on which the matrix is to be bonded is grooved by a pointed tool.

Fig. 4 is a section on the plane 4—4 of Fig. 3.

Fig. 5 shows, in section and perspective, somewhat enlarged, the structure of Fig. 2 after the grooving has been finished.

Fig. 6 shows, in section and perspective, a portion of Fig. 5, the scale being greatly enlarged.

Fig. 7 is similar to Fig. 6, showing an alternate arrangement.

Fig. 8 shows, in section and perspective, on the scale of Fig. 2, the abrasive-containing matrix fully formed and hardened in place.

Fig. 9 is similar to Fig. 8, showing in broken lines the retaining walls which are machined away at the conclusion of the formation of the matrix.

Fig. 10 is a view similar to Fig. 8, showing the matrix fully formed on the periphery of the wheel, ready for use.

Referring to the annexed drawing, wherein like reference characters designate like parts in the various figures—

An abrasive wheel may be of several forms. In the form herein shown for purposes of illustration, it comprises a disc portion 11 and an annular rim 12 projecting laterally of the plane of the disc. Upon a surface 13 of the annular rim 12 is positioned a hardened abrasive-containing matrix 14. For illustrating the present invention it will be assumed that the material of at least a portion of this matrix is applied to surface 13 in liquid form and is heat-hardened in place, and that successive layers are built up in this manner to provide the desired depth.

While surface 13 may be formed of any one of a number of available materials, it is often desirable that the entire wheel should be formed of a light strong metal such as aluminum. Aluminum is particularly effective, not only because it is light, but because it may be easily turned and polished. A smooth aluminum surface, however, does not in itself form a satisfactory bond with an abrasive-containing matrix heat-hardened upon it. The same is true of copper and other ductile materials of the types which are "sticky" when machined or turned. This invention permits the bonding of such abrasive matrix directly upon such metal.

In carrying out our invention, we form the annular rim 12 somewhat wider than will ultimately be required, and cut away sufficient material to form a broad, shallow channel 15 therein having a smooth or nearly smooth floor 16, and side walls 17, 18 whose height above the floor 16 is the same as or slightly greater than the desired depth of the abrasive-containing matrix to be formed in the channel. The width of channel 15 equals the desired width of the annular band of abrasive-containing matrix 14. The channel 15 may be formed by machining, i. e., by cutting away waste metal by the use of a tool in a turning lathe, or in any other similar manner.

We then place the wheel in a lathe and turn it slowly under a cutting tool 19 in a suitable holder 20. Tool 19 is of tungsten carbide, chilled

steel, or other hard material and is provided with a sharp point or sharpened edge. Tool 19 is applied with a reverse or negative rake, and in such manner as to plow a shallow groove 21 in the smooth floor 16 of the channel 15. During the turning of the wheel, tool 19 is moved gradually from one side of the channel 15 towards the other, thereby forming a spiral or helical groove. The depth of the groove may be suited to individual requirements. It may be a few thousandths of an inch in depth, or it may be somewhat deeper than the groove usually employed on phonograph records. If desired, the groove need not be helical or continuous but can be cut in the form of a series of concentric circles, the differences in diameter being such as to space the grooves at desired distances apart. We prefer a helical groove, with adjacent courses spaced about .015 inch apart on centers, the groove being slightly deeper than the groove in the usual commercial phonograph record.

In plowing groove 21, the tool 19 is arranged to remove little or no metal but to cause the formation of a lip 22 at each side of the groove, and the reverse or negative rake of the tool causes the formation along each lip of a series of jagged projecting tongues of metal, integral with the metal of the surface being worked upon and projecting upwardly above the general level thereof. These jagged projections of the metal, shown diagrammatically at 23, can be clearly seen with the naked eye where the grooves are fairly deep, and in smaller and more closely packed grooves can be clearly seen under a glass.

Where successive courses of a continuous helical groove are closely spaced, the common lip or ridge between adjacent courses of the groove carries along its crest a continuous row of these jagged projecting tongues of metal. If the courses are further removed apart, as suggested in Fig. 7, the lip at either side of the groove will have a projecting series of tongues of metal.

After the floor 16 of channel 15 has been prepared in the manner stated, abrasive-containing matrix may then be formed between the side walls 17, 18 of the channel in any suitable manner. For this purpose we prefer to employ the method of forming an abrasive matrix which is shown in our co-pending application, Ser. No. 212,306, building up successive layers of abrasive-containing glass fabric impregnated with a heat-hardening varnish. The first layer may be a primer which is applied in liquid form upon the grooved surface and heated to render it tacky. This layer forms an intimate and effective bond with the projecting tongues of metal and forms the base upon which successive layers of fabric and impregnating diamond dust and varnish with suspended diamond particles, are laid and heat-hardened. Each layer is applied separately, and baked in place before the next layer is applied. This procedure is followed layer by layer until abrasive-containing material 14 of suitable depth has been built up as indicated in Fig. 8.

When the matrix has been entirely formed and the final baking has been completed, the side walls 17, 18 are then machined away, the parts removed being indicated by dotted lines in Fig. 9. The result is to produce the finished structure indicated in Fig. 10 and Fig. 1.

It appears that the varnish or other heat-hardenable material which is applied in liquid

form upon the floor 16, prepared as herein described, fills the groove 21 and the tongues 23 become embedded therein. When the initial layer or layers of varnish material have been baked in place, the result is to produce a very effective and secure bond between the metallic surface and the abrasive matrix which is formed thereon. We have found that abrasive wheels made in this manner have a pronouncedly long life, may be used at higher speeds, and will not flake or chip in use.

The angle at which the tool 19 is applied must be determined by trial, depending upon the nature and physical property of the metal being grooved. The projecting tongues of the metal appear to be formed only when the tool is given a reverse or negative rake. The phenomenon has its chief usefulness in connection with the ductile metals such as aluminum and copper.

We claim:

1. In the method of preparing an annular ductile metallic surface of a high-speed grinding wheel to receive and retain a layer of abrasive-containing matrix thereafter to be applied to said surface, the step of machining said surface with a hardened tool applied with a reverse rake in relation to its direction of travel upon said surface and at such an angle thereto as to form a series of minute tongues of metal integral with the metal of said surface and projecting upwardly above the general level of said surface.

2. In the method of preparing an annular ductile metallic surface of a high-speed grinding wheel so as to adapt the same to retain a layer of abrasive-containing matrix thereafter to be applied to said surface, the step of plowing in said surface a shallow groove by means of a sharpened tool applied with a reverse rake in relation to its direction of travel upon said surface and at such an angle thereto as to form a series of minute upwardly-projecting tongues of metal integral with the metal of said surface along a lip of said groove.

3. In the method of preparing an annular ductile metallic surface of a high-speed grinding wheel so as to adapt the same to retain a layer of abrasive-containing matrix thereafter to be applied to said surface, the step of plowing in said surface a series of closely-spaced shallow circular grooves by means of a sharpened tool applied with a reverse rake in relation to its direction of travel upon said surface and at such an angle thereto as to form a series of minute upwardly-projecting tongues of metal integral with the metal of said surface along the lip between adjacent courses of said groove.

4. In the method of preparing an annular ductile metallic surface of a high-speed grinding wheel so as to adapt the same to retain a layer of abrasive-containing matrix thereafter to be applied to said surface, the step of plowing in said surface a shallow continuous helical groove, with the courses thereof relatively close together, by means of a sharpened tool applied with a reverse rake in relation to its direction of travel upon said surface and at such an angle thereto as to form a series of minute upwardly-projecting tongues of metal integral with the metal of said surface along the lip between adjacent courses of said groove.
